ENGINE STARTER DRIVE

Donald L. Miller, Pine City, N. Y., assignor to
 Bendix Aviation Corporation, a corporation of
 Delaware

Application December 3, 1945, Serial No. 632,526

15 Claims. (Cl. 74—7)

1 The present invention relates to an engine starter drive and more particularly to that type of starter which remains in operative connection with the engine to be started until the operator acts to interrupt the starting operation. In this type of starter, the driving connection between the starting motor and the engine to be started may be continued by the operator until the engine is self-operative regardless of momentary or isolated impulses therefrom.

It is an object of the present invention to provide a novel engine starter of the above type which is simple, reliable and of small dimensions.

It is a further object to provide such a device in which means under the control of the operator are used to initiate and continue the starting operation regardless of weak explosions and momentary impulses of the engine to be started.

It is a further object to provide such a device wherein a plunger member, which may be under the control of the operator, governs the disengaging movement of an engine driving member during the starting operation.

It is a further object to provide such a device in which a rotary member cooperates with a plunger member to hold the engine driving member in either operative or inoperative position.

It is a further object to provide such a device in which a rotary member locks an engine driving member in operative position by means of a plunger member, the unlocking function of the rotary member being accomplished by the application of a manually controlled or engine operated drag member.

It is another object to provide such a device having a centrifugally controlled member in association with a plunger member which is connected to an engine driving member for longitudinal movement, to prevent continued movement of the engine driving member away from the engine member until a reliable engine start is secured.

It is another object to provide such a device wherein the above mentioned plunger member is supported and connected so as to be freely slideable regardless of centrifugal forces acting thereon.

It is also an object to provide such a device having an overrunning clutch and means responsive to centrifugal force for frictionally augmenting the overrunning torque of the clutch in the driving connection for the engine driving member whenever excessive rotational speeds are developed during the starting operation.

A still further object is to provide such a de-

vice in which a rotary lock for the above mentioned plunger member is provided with means for enabling said plunger to forcibly retract to idle position if the contact pressure between the plunger and lock is increased beyond a critical value as a result of a defective clutch or otherwise.

Further objects and advantages will be apparent to those skilled in this art by referring to the following description and accompanying drawings, in which:

15 Fig. 1 is a side elevation partly in section of a preferred form of the invention shown in idle position;

15 Fig. 2 is an end view of the device shown in Fig. 1 with the rotary lock in position to prevent drifting of the pinion away from idle position;

20 Fig. 3 is a view similar to Fig. 1 showing the starting drive in operative position;

20 Fig. 4 is a view partly in section of a modification of the mechanical detent shown in Fig. 3, illustrating a vacuum-operated detent for the rotary locking member;

25 Fig. 5 is a view similar to Fig. 1 showing the starting drive partly demeshed in overrunning or locked position;

30 Fig. 6 is an end view from the left of Fig. 5;

30 Fig. 7 is a perspective view of the screw shaft, casing and control nut of the starting drive in disassembled relation and partly broken away;

35 Fig. 8 is a fragmentary detail view in side elevation, partly in section, of an embodiment of the present invention having a centrifugally released type of locking member;

35 Fig. 9 is a detail of a rotary locking member having an alternative form of conical opening therein;

40 Fig. 10 is a side elevation partly in section of another embodiment of the present invention;

40 Fig. 11 is a view of the left end of the starting drive as shown in Fig. 10;

45 Fig. 12 is a perspective detail view of the rotary locking member and the cooperating plunger and screw shaft of Fig. 10, shown in disassembled relation; and

45 Fig. 13 is a section taken substantially on the line 13—13 of Fig. 10.

In the form of the invention shown in Fig. 1, a power shaft 1 which may be the armature shaft 50 of a starting motor not shown, having an extension 2 of reduced diameter forming a shoulder 3, serves as a mounting member to which an operating member in the form of a screw shaft 4 is fixed in any suitable manner as by means of an anchor pin 5 and lock wire 6. Screw shaft 4

55

is provided at its forward end with threads 7 and at its rear end with a head portion 8 of enlarged diameter. A control member in the form of a nut 9, having a flange 11 and a smooth cylindrical extension 12, is mounted by means of threads 13 on the screw shaft 4. An engine driving member in the form of a pinion 14 is slidably journaled on the power shaft 1 for traversal into engagement with an engine member such as a gear 15 to crank the engine.

Means for actuating the pinion 14 by the control member 9 are provided comprising a resilient member in the form of a rubber sleeve 17, a casing member 18 and a dental clutch comprising a driving plate 23 and a driven plate 24. Sleeve 17 is seated upon the control nut 9 and frictionally bears against the flange 11 thereof. In order to hold the pinion 14, clutch 16 and the rubber sleeve 17 assembled to the control nut 9, the casing member 18 is formed as a barrel having a flange 19 overreaching the rear side of control nut flange 11 and having longitudinal slots 21 in the opposite end which received lugs 22 on the driving clutch plate 23. The driven clutch plate 24, which is fixed to the pinion 14 by any suitable means such as welding or brazing at 25, is held normally disengaged from plate 23 by a disc spring 26 positioned between the plates, and the separation is limited by a clutch housing ring 27 which is fixed in the end of casing 18 in a suitable manner as by spinning over the end of the casing so as to lock clutch plate 23 in said casing. A thimble 20, anchored to the casing 18 and slidably fitting the nut 9, is preferably provided to enclose the rubber block 17 and assist in the frictional transmission of torque from said block to the clutch plate 23.

According to the present invention, means are provided for maintaining the engagement of the pinion 14 with the engine gear while the starter is energized, regardless of non-continuous explosions and impulses of the engine. For this purpose, the flange 19 of the barrel 18 is recessed on the inner side thereof to form a clearance space 28 and an extended narrowed lip 29, and an axially movable plunger or rod 31 is slidably mounted in an opening 32 in the head 8 of screw shaft 4 and provided with a groove 33 forming a swivel connection with the lip 29 of casing 18 whereby axial movements of the pinion and casing assembly are transmitted to the plunger 31. The lip 29 is arranged to bear in the bottom of the groove 33 so as to assist in properly aligning the plunger 31 for free movement in the opening 32.

Means for opposing or limiting retrograde movement of plunger 31 so as to prevent disengagement of the pinion 14 from the engine gear 15 are provided in the form of a rotatable latch or detent thimble 34 mounted on the screw shaft head 8 with freedom for limited rotation and adapted to cover the opening 32 therein. An opening 36 of substantially greater diameter than the plunger 31 is provided in the thimble 34 to allow the rear end of the plunger to project through the thimble when the thimble is rotated to bring opening 36 into alignment with opening 32. Thimble 34 is normally maintained in position to substantially cover the opening 32 by a torsion spring 40 anchored at its ends to the screw shaft and thimble.

Means are provided for enabling the plunger 31 to rotate the locking thimble 34 and push its way out through the opening 36 when the demeshing force on the plunger exceeds a definite

value. As here shown, this is accomplished by forming a conical bevel or countersink 39 on the inner side of the opening 36 in the locking disc.

Means for attaching the thimble to the screw shaft head 8 and limiting its rotation thereon are provided in the form of studs 41 seated in said head and extending through arcuate slots 42 in the thimble. For the purpose of reducing the frictional contact between the screw shaft head and thimble to a minimum, circumferential ridges 43 and 44 of semi-circular cross section are formed on the head 8 in an advantageous location to promote free rotation of the locking member.

The locking means 31, 34 is also arranged to operate as a means for preventing drifting of the pinion 14 out of idle position. For this purpose, a circumferential recess 37 is formed near the rear end of the plunger 31, having an inclined shoulder 38 against which the angular inner edge of the opening 36 is pressed by the spring 40 when the parts are in idle position.

Manually controlled means for causing rotation of the rotary lock member 34 into a position to free the plunger 31 are provided in the form of a frictional drag member 46 attached to the armature 47 of a magnetic starting switch 48. Drag member 46 may be provided with a tip of non-metallic material of suitable frictional and wearing properties such as cork. The starting switch is located in a starting circuit comprising a battery 49 grounded at 51, a lead 52 connecting the battery to the starting switch and a lead 53 connecting the switch to the starting motor SM which is grounded at 54. A lead 55 connects the battery 49 to a manual switch 56 which controls the energization of the starting switch coil 51, the circuit of which is completed through the ground at 58.

In operation, closure of the manual switch 56 permits current from battery 49 to flow through the lead 55, switch 56 and switch coil 51 to ground at 58, thus energizing coil 51 and closing starting switch 48. The starting circuit is thereby completed from battery 49 through lead 52, starting switch 48, lead 53 to starting motor SM and ground 54. Since the frictional drag member 46 is mounted on the switch armature 47, it is raised out of contact with the rotating lock member 34 by the closure of the starting switch. Rotation of power shaft 1 and screw shaft 4 by the starting motor causes control nut 9 and its associated parts to advance along the screw shaft, pushing the pinion 14 into mesh with the engine gear 15 and against the stop shoulder 3. When the forward motion of the pinion 14 is arrested by the shoulder 3, subsequent rotation of the screw shaft 4 closes the clutch 23, 24 against the pressure of the spring 26 and compresses the resilient sleeve 17 which thus completes a yielding driving connection.

When the engine becomes reliably self-operative, the operator opens the manual switch 56 which in turn opens the starting switch 48. The frictional drag member 46 thereupon descends and bears on the thimble 34 causing it to be retarded with respect to the screw shaft 4 so as to bring the opening 36 thereof into registry with the plunger 31 and thus free the plunger for backward movement, thereby permitting the pinion 14 to demesh from the engine gear due to the acceleration of the control nut by the torque transmitted from the pinion back through the overrunning clutch 23, 24 by virtue of the spring 26. It will be understood that the ex-

terior surface of the flange 35 on the lock member 34 may be knurled or otherwise formed so as to increase the friction of the drag member 46 thereon if desired.

If a false start should occur, that is if one or more sporadic explosions of the engine should take place, the operator maintains the manual switch 56 closed, and the pinion 14 is prevented from coming out of mesh with the engine gear 15 by the lock member 34 which is held by the torsion spring 40 against the studs 41 in a position to obstruct the rearward movement of the plunger 31.

If the clutch 16 should fail to disengage for any reason such as the presence of rust or foreign matter, it may be desirable to demesh the pinion from the engine gear even though the operator fails to open the starting switch. This is accomplished as shown by bevelling the end of the plunger 31 and correspondingly flaring the opening 36 in the lock member 34. The end of the plunger 31 is thus adapted to engage the inclined surface 39 of the lock member as illustrated in Fig. 9, whereby an excess of longitudinal pressure on the plunger will force the lock member 34 to rotate far enough to free the plunger and permit demesh of the pinion. When the plunger reaches idle position, the lock member is urged into the recess 37 adjacent the shoulder 38 so as to prevent the pinion 14 from drifting out of idle position.

A second embodiment of the present invention is illustrated in Fig. 8 in which a centrifugal member in the form of a steel ball 59 is mounted in a radial opening 60 in the head 3 of screw shaft 4 and pressed inwardly against the plunger 31 by a circular spring 61 to govern the reciprocating motion of the plunger. In this form of the invention, the ball 59 is arranged to engage in the groove 37 to resist the demeshing of the pinion. The plunger 31 is also provided with a second groove 65 adapted to register with the ball 59 when the parts are in idle position, whereby the ball serves as an anti-drift detent for the drive. In order to demesh the pinion from the engine gear, it is necessary for the demeshing force on the plunger 31 to build up to a magnitude large enough to overcome the spring 61 and force the ball up the inclined shoulder 38 of groove 37. When the drive is rotating rapidly, however, the centrifugal force of the ball 59 and spring 61 tends to balance the inward pressure of the spring, whereby the pinion is allowed to freely demesh. If only spasmodic impulses are transmitted to the pinion 14 by the gear 15, as in a false start of the engine, the spring 61 exerts pressure on the detent 59 to prevent longitudinal movement of the plunger 31 and to keep the pinion in mesh with the engine gear 15.

A further modification of the present invention is illustrated in Fig. 4 in which a frictional drag member 68 is actuated by a vacuum-powered device 69 to perform the function of the drag member 46 of Fig. 1. This device has a vacuum chamber 71 connected by a tube 72 to the intake manifold 73 of an engine not further shown. A spring 74 bearing against a flexible diaphragm 75 normally holds the drag member out of contact with thimble 34. When the engine starts, the vacuum produced in the intake manifold 70 acts on the diaphragm to overcome the spring and press the drag member against the thimble, thus permitting the pinion to demesh from the engine gear.

In Figs. 10 to 13, there is illustrated an em-

bodiment of the invention incorporating a yielding member on the rotatable lock member which permits retraction of the plunger 88 when the demeshing pressure thereon is excessive. In this form of the invention, a screw shaft 76 is provided having a head portion 77 formed on its rear face with a recess 78 in which is seated a torsion spring 79 which is arranged to control a rotatable locking thimble 83. In order to attach the spring to the screw shaft and thimble, the ends of the spring are bent outwardly, one end anchored in a hole 81 on the screw shaft 76 and the other end in a hole 82 on the rotatable lock member 83, so located as to place the spring under suitable stress. Lock member 83 is journalled at 84 on the head 77 and is held thereon by a lock ring 85 seated in a recess 86, thus confining the spring 79. An elongated hole 87 is provided in the wall of the thimble 83, and a plunger 88 which is slidably mounted in the head 77 of the screw shaft and has a swivel connection with the barrel member 18 is arranged to project through said opening when the parts are in idle position.

25. Means for yieldingly opposing projection of the plunger 88 through the opening 87 so as to hold the pinion in mesh with the engine gear is provided in the form of a curved flat spring 89 having one end anchored at 90 to the thimble 83 and extending at its other end partly over the elongated hole 87.

Normally, the lock member 83 is rotated by the torsion spring 79 to place the end of the flat spring 89 over the end of the plunger 88 while 35. the drive is in cranking position. Means for limiting the rotation of the lock member 83 are provided in the form of inturned lugs 91 and 92 struck from the radial surface of the lock member so as to project into slots 93 and 94 40 in the rear face of the screw shaft head 77. Slots 93 and 94 are sufficiently wider than lugs 91 and 92 to permit rotational movement of the lock member 83 from locked position to unlocked position; that is, to allow spring 89 to be moved 45 into and out of the path of the plunger 88. As shown in Figs. 10 and 13, speed responsive means are provided for making the clutch 23, 24 more effective at excessive overrunning speeds to transmit torque from the pinion 14 through the rubber 60 sleeve 17 to control nut 9 for the purpose of demeshing the pinion. This means is supplied in the form of a centrifugal brake member 95 pivoted at 96 on the pinion and biased inwardly by a spring 97 anchored at 98 and attached by lug 99 to said weight.

In the operation of the structure here shown, energization of the starting motor (not illustrated) moves the pinion 14 into mesh with the engine gear 15 and cranks the engine as described in the previous embodiment. If a false start occurs, the pinion attempts to demesh, pushing the plunger 88 back until it bears against the flat spring 89 in which position the pinion 14 will still be partially meshed with the gear 15 while clutch 16 overruns. When the engine gear slows down, the pinion is moved back into mesh therewith and cranking is resumed. After the engine is started, the operator releases the starting switch 43, whereby the frictional drag member 46 comes in contact with the lock member 83 and retards it with respect to the screw shaft, thus moving the spring 89 out of the path of the plunger 88 so that the parts can return to idle position. If the clutch 16 should 75 fail to release for any reason, increased pressure

will be transmitted from the barrel 18 to the plunger 88, which then flexes the flat spring 89 backward and permits the pinion 14 to demesh.

Under certain circumstances, the unaided overrunning torque of the clutch 23, 24 may not be great enough to overcome the resistance of spring 89 and permit the pinion 14 to demesh from the engine gear 15. If this should occur, the pinion continues to rotate with the engine gear after the engine is started and consequently attains a very high speed. A large centrifugal force is thereby generated in the friction brake member 95 to press it heavily against the clutch disc 23 and increase the torque delivered through the clutch to a magnitude great enough to force the plunger 88 backward, thus deflecting the spring 89 and demeshing the pinion.

Although certain embodiments of the invention have been shown and described in detail, it will be understood that other embodiments are possible and that various changes may be made in the design and arrangement of the parts without departing from the spirit of the invention as defined in the claims appended hereto.

What is claimed is:

1. In an engine starter drive, a motor shaft, a screw shaft fixed thereon having a head portion, a control nut threaded on said screw shaft, a pinion slidably journaled on said motor shaft for meshing with and rotating a gear on the engine to be started, means for driving said pinion including a yieldable member and a clutch, a plunger member axially traversing the head of said screw shaft, means connecting the plunger to the pinion for longitudinal movement in unison while permitting rotation of the pinion relative to the plunger, and means including a rotatable lock member arranged to obstruct traversal of said plunger member in a direction to demesh the pinion.

2. In an engine starter drive, a motor shaft, a screw shaft fixed thereon having a head portion, a control nut threaded on said screw shaft, a pinion slidably journaled on said motor shaft for meshing with and rotating a gear on the engine to be started, means for driving said pinion including a yieldable member and a clutch, a plunger member axially traversing the head of said screw shaft, means connecting the plunger to the pinion for longitudinal movement in unison while permitting rotation of the pinion relative to the plunger, and means including a centrifugal member operable on said plunger member for opposing longitudinal movement of said plunger and pinion.

3. In an engine starter drive, a motor shaft, a screw shaft fixed thereon having a head portion, a control nut threaded on said screw shaft, a pinion slidably journaled on said motor shaft for meshing with and rotating a gear on the engine to be started, means for driving said pinion from said control nut including a yieldable member and a clutch, a plunger member axially traversing the head of said screw shaft, means connecting the plunger to the pinion for longitudinal movement in unison while permitting rotation of the pinion relative to the plunger, said plunger having a circumferential groove and detent means cooperating with said groove to retain said plunger member in idle position.

4. An engine starter drive as set forth in claim 2, including further an annular elastic member surrounding said plunger and cooperating with the centrifugal member to oppose longitudinal movement of the plunger and pinion.

5. In an engine starter drive, a motor shaft, a screw shaft fixed thereon having a head portion, a control nut threaded on said screw shaft, a pinion slidably journaled on said motor shaft for meshing with and rotating a gear on the engine to be started, means for driving said pinion from said control nut including a yieldable member and a clutch, a plunger member axially traversing the head of said screw shaft, means connecting the plunger to the pinion for longitudinal movement in unison while permitting rotation of the pinion relative to the plunger, a rotatable lock member surrounding said plunger member for opposing longitudinal movement thereof and means for rotating said lock to unlocking position when the demeshing force on said plunger reaches a predetermined value.

6. An engine starter drive as set forth in claim 5 in which the rotatable lock for the plunger has an inclined surface cooperating with said plunger to rotate said lock to unlocking position when the retracting force on said plunger reaches a predetermined value.

7. In an engine starting mechanism, a starting circuit including a starting switch and a starting motor; an engine starter drive mounted on the motor shaft including a headed screw shaft fixed thereon, an engine driving member slidably journaled on said motor shaft for engaging and rotating an engine member, and means for driving said engine driving member from said screw shaft, a slideable rod in the head of said screw shaft having a connection at one end thereof to the engine driving member, a rotary lock for limiting the demeshing movement of said rod and engine driving member, said rotary lock being swiveled on said head for movement into and out of locking position, spring means urging the lock into locking position, and means responsive to opening of said starting switch for rotating the lock out of its locking position.

8. In an engine starter drive, a motor shaft, a screw shaft fixed thereon having a head portion, a control nut threaded on said screw shaft, a pinion slidably journaled on said motor shaft for meshing with and rotating a gear on the engine to be started, means for driving said pinion from said control nut including a yieldable member and a clutch, a plunger member axially traversing the head of said screw shaft, means connecting the plunger to the pinion for longitudinal movement in unison while permitting rotation of the pinion relative to the plunger, a rotary detent for controlling longitudinal movements of said plunger, and means responsive to self-operation of the engine for moving the detent to free said plunger for backward movement.

9. In an engine starter drive, a motor shaft, a screw shaft fixed thereon having a head portion, a reciprocating member extending through said head portion having a circumferential groove, a control nut threaded on said screw shaft, a pinion slidably journaled on said motor shaft for movement into and out of engagement with a gear on the engine to be started, a driving connection between said nut and pinion, a casing member connected for axial movement to said pinion and having an inwardly extending flange seated within said groove on said reciprocating member, and locking means for obstructing rearward movement of said reciprocating member sufficient to permit demeshing of said pinion.

10. In an engine starter mechanism, a starting circuit including a motor and a starting switch, a screw shaft fixed on the motor shaft having a head portion, a control nut threaded on said screw shaft and having a flange thereon, a resilient sleeve seated against said flange, a pinion slidably journaled on said motor shaft to mesh with and rotate a gear on the engine to be started, means connecting the resilient sleeve to the pinion including an overrunning clutch and a flanged casing enclosing said resilient sleeve under initial compression, a reciprocating member slidably traversing the head portion of said screw shaft and having a swivel connection to the flange of said casing, a spring-biased rotary lock member journaled on the head of said screw shaft and opposing longitudinal movement of said reciprocating member, means for restricting relative rotation between said lock member and head, and a frictional drag member movable into engagement with said lock member by opening said starting switch and operative to cause rotation of the lock member on the screw shaft into position to release the reciprocating member.

11. In an engine starter, a power shaft, a screw shaft fixed thereon, said shaft having a rearward portion of enlarged diameter, a control nut threaded on said shaft, a pinion slidably journaled on said power shaft for traversal into mesh with and rotation of an engine gear, a driving connection between said control nut and pinion including an enclosure member, an elastic member and a clutch, a reciprocating member axially traversing the enlarged portion of said screw shaft and having a thrust connection to said enclosure member, a rotatable lock member journaled on the enlarged portion of said screw shaft cooperating with the reciprocating member to hold said pinion in mesh with said engine gear, a spring ring for positioning said lock member on the screw shaft in locking position, and means including an elastic member on said lock member for engaging the reciprocating member to hold the pinion in mesh, but adapted to yield on overload to permit demeshing of said pinion while said lock member is in locked position.

12. In an engine starter, a power shaft, a screw shaft fixed thereon, said shaft having a rear-

ward portion of enlarged diameter, a control nut threaded on said shaft, a pinion slidably journaled on said power shaft for traversal into mesh with and rotation of an engine gear, a driving connection between said control nut and pinion including a casing member, an elastic member and a clutch, a reciprocating member axially traversing the enlarged portion of said screw shaft and having a thrust connection to said casing member, and means for opposing retrograde motion of said reciprocating member while the starting drive is operating including a lock member rotatably mounted on the screw shaft having a flat spring mounted thereon with its free end in the path of travel of said plunger.

13. In an engine starter, a power shaft, a screw shaft fixed thereon, said shaft having a head portion, a control nut on said shaft, a pinion slidably journaled on said power shaft for traversal into mesh with and rotation of an engine gear, a driving connection between said control nut and pinion including a casing member, an elastic member and an overrunning clutch, a reciprocating member axially traversing said head portion and having a thrust connection to said casing member, a lock member journaled on said head portion for cooperating with the reciprocating member to hold said pinion in mesh with said engine gear, said head portion having transverse slots, and said lock member having lugs engageable therein for limiting relative rotation thereof.

14. An engine starter drive as set forth in claim 13 including further speed responsive means for supplementing the overrunning torque of said clutch when rotated at excessive speed.

15. An engine starter drive as set forth in claim 13 including further a centrifugal clutch member mounted on said pinion and effective above a predetermined speed of rotation to transmit torque from the pinion to said control nut.
